(57) CLAIM

The ornamental design for a low profile light fixture, as shown and described.

DESCRIPTION

FIG. 1 is a perspective view of a low profile light fixture, showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines showing the base thereof in FIGS. 1-6 are included for illustrative purposes and form no part of the claimed design.

1 Claim, 4 Drawing SheetsFIG. 1

FIG. 2

FIG. 3

FIG. 5
